CLOTHES DRIER

Joseph W. Jensen, Chicago, Ill., assignor to Electric Household Utilities Corporation, Chicago, Ill., a corporation of Illinois

Application June 23, 1937, Serial No. 149,827

13 Claims. (Cl. 34—26)

The present invention relates to improvements in clothes driers of the type adapted for domestic or household use.

There are numerous forms of driers of the above mentioned class now commercially available, practically all of which are constructed in a manner requiring the use of a substantially closed chamber, usually formed of sheet metal, in which is employed suitable heating apparatus, either electrical, steam, or gas.

The primary purpose of driers of this type is to reduce the burden usually attendant upon the clothes washing operation in the home, in that it eliminates the necessity and annoyance of stringing clothes-line and using clothes pins for securing the various articles thereto, and the problem of properly supporting the line to prevent soiling of the clothes. Such devices, also permit expeditious drying of the washed articles in a period of time materially less than that required when suspended in a normal manner on a clothes line, either in-doors or out-doors. Also, such devices always assure proper drying of the clothes immediately after washing, irrespective of weather conditions. When clothes or other washed articles are hung on a line out-of-doors, in addition to the substantial labor involved, there is always great danger that the drying thereof will not be promptly effected; in other words, weather conditions are always a controlling factor. Driers of this class definitely remove the hazards of proper clothes drying and is no-wise subject to or dependent upon weather conditions.

One of the objects of the present invention is to produce a novel and improved clothes drier of the character indicated, which is of simple and rugged construction, highly efficient and capable of economical manufacture.

Another object of this invention resides in the provision, in a drier of the character described, of elements so that the natural convection currents of the burner cause an influx of a continuous supply of fresh air for admixture with said natural convection currents and causes said admixture to circulate around and over the articles to be dehydrated; said arrangement of elements being such as to preclude any appreciable amount of recirculation of the admixed air within the drier.

A further object is to provide an improved drier of the character indicated comprising a frame structure formed to provide a relatively large opening at its upper end to constitute a draft outlet and a sheet of flexible material sur-

rounding the frame and constituting the vertical walls thereof for enclosing the wet or moist articles suspended on the frame structure; said flexible sheet material terminating a short distance above the floor to provide a draft inlet from all directions for assuring substantial circulation of the heated air currents around the wet or moist articles suspended in the frame for effecting expeditious drying or dehydration thereof.

Still another object of the invention resides in the provision of an improved construction, which may be quickly and easily assembled, or erected, or dismantled for convenience in shipping or storage.

Other objects and advantages will appear in the following description taken in connection with the accompanying drawings, in which:

Fig. 1 is a view, in side elevation, of a clothes drier embodying the present invention, portions being broken away to show details of construction.

Fig. 2 is a plan or top view.

Fig. 3 is an end elevation with portions of the flexible covering broken away to show details of construction.

Fig. 4 is a fragmentary view looking down on the upper end of the frame structure.

Fig. 5 is a fragmentary sectional view taken through the upper end of one of the end standards of the frame.

Fig. 6 is a fragmentary end view similar to Fig. 5 showing, a portion of a flexible curtain in position thereon, looking from the interior of the drier.

Fig. 7 is a sectional view through one of the end standards, showing the support for the free ends of the rods, and taken as indicated at line 7—7 in Fig. 3.

Fig. 8 is a fragmentary side view of the rod support shown in Fig. 7.

Fig. 9 is a transverse section through the other standard, showing a fragmentary portion of the rod mounting, taken as indicated at line 9—9 in Fig. 1.

Fig. 10 is a vertical section through the rod mounting, taken as indicated at line 10—10 on Fig. 9, showing the supporting arrangement for the rods.

Fig. 11 is a fragmentary view part in elevation and part in section, taken at line 11—11 on Fig. 9, showing the rod support.

Fig. 12 is a horizontal staggered sectional view, taken as indicated, at line 12—12 on Fig. 1, showing the burner construction, part in section and part in elevation.

Fig. 13 is a vertical view, part in section and part in elevation, taken at line 13-13 on Fig. 12.

Figs. 14 and 15 are transverse sectional views through the fuel supply end of the burner, taken 5 at lines 14-14 and 15-15, respectively, on Fig. 12.

Fig. 16 is an enlarged fragmentary vertical section through the lower portion of the drier, taken as indicated at line 16-16 on Fig. 1.

Fig. 17 is a detail sectional view, taken at line 10 17-17 on Fig. 16.

For purpose of illustration, I have herein shown the present invention as embodying heating apparatus in the form of a gas burner. It will be apparent, however, that other suitable forms 15 of heating apparatus may be employed with equal facility, and with substantially equivalent efficiency and other similar advantages.

The device shown in the drawings include a frame structure, comprising two spaced-apart uprights or standards 10, preferably in the form of tubular members or pipes, the lower ends of each of which are rigidly secured in "five-way" pipe fittings 11, by set screws 11a. Rigidly secured by 20 tapered pins 11b, in a pair of opposed openings 25 in each fitting, are a pair of oppositely extending substantially horizontal members 12, the outer ends of which are down-turned to engage the floor, and constitute feet for the frame structure. The standards 10 are rigidly connected together 30 at their lower ends by a horizontally extending tubular member or pipe 14, which, as hereinafter described, also constitutes the gas burner. The opposite end portions of the pipe 14, extend through a pair of aligned openings in the fittings 35 11, and secured thereto by set screws 11c. The upper ends of the standards are rigidly connected together by a horizontally disposed closed loop frame 15, which, as shown, is of substantially rectangular form and is composed of two oppositely disposed generally U-shaped rods 16, the 40 ends of which are formed with downturned terminal portions 17, as seen in Fig. 5 adapted to be seated in sockets 18, formed in the upper ends of the standards 10. The sockets are formed by depressing diametrically opposite portions of the 45 upper ends of said standards, as seen in Figs. 4 and 5. This construction thus permits quick and easy mounting or detachment of the loop frame members 16 with respect to the standards. The 50 loop frame portion 15 thus defines an opening of substantial size at the upper end of the drier, which at all times serves as a draft outlet.

Suspended on the said members 16 of the loop frame is a sheet of flexible material in the form 55 of a curtain, indicated at 19, the upper edge of which is folded inwardly on itself and stitched thereto, as indicated at 20, to form a loop hem adapted to be threaded onto the loop frame members 16 by merely removing a pair of adjacent 60 terminal ends 17 from the sockets of the standards 10. Desirably, this flexible curtain of sheet material, which may be cloth or the equivalent, is formed so that it may be extended around the entire frame structure, and thereby serve to form 65 in effect a continuous vertical wall constituting the closure for the drier. The upper marginal edge of the curtain preferably is cut away, as indicated at 21, in Fig. 6, to freely accommodate the terminal portions 17 of the loop frame for 70 connection in the sockets of the standards. Desirably, the vertical edges of the curtain terminate at one end adjacent one of the standards, as seen in Fig. 3, and said vertical edges may be secured together in any convenient manner, such as 75 herein shown, by conventional snap buttons 22.

To gain access to the interior of one end of the drier, the flexible curtain is drawn along the supporting loop frame member 16, to provide an opening of suitable size. The lower edges of the flexible curtain, as seen in the drawings, terminate a short distance above the level of the floor so as to provide natural air draft for the gas burner from all directions. By virtue of this arrangement the flexible curtain 19 may be quickly and easily removed for washing or cleansing 10 and again replaced on the frame loop 15.

Mounted on one of the standards 10 are one or more (two being herein shown) transversely extending substantially horizontal supports 25, which as seen in Fig. 10 are of generally tubular 15 cross section, each formed of two sheet metal channel sections 26 and 27, rigidly secured together, as by spot welding. The members 25 are rigidly attached to an upright or standard 10 by a plurality of bolts 27a. The lateral extent of 20 these members or supports 25 approximately define the width of the drier structure, and carried by each of these supports are a plurality of horizontally extending transversely spaced-apart supporting elements, herein shown in the form of rods 29, each having a down-turned end portion 30, journaled in both top and bottom walls of the support 25, to provide a pivot or hinged connection which permits said rods to be swung laterally, and it is to be understood that said 25 hinged connection is of sufficient rigidity to properly support the weight of the rods. However, to assist in supporting the free ends of said rods in operating position, and for properly positioning the same to maintain a definite spaced-apart 30 relationship to each other, I provide transversely extending supports 32 on the opposite standard 10, at approximately the same horizontal level as supports 25. Connected to each of said supports 32 is a collar 33 adapted to be rigidly secured in proper position on the standard by means of set screws 34. Said supports 32 extend approximately the same distance on opposite sides of the standards, and are each formed with a plurality of transversely spaced-apart seats 36 for the free 35 ends of the rods 29, as seen in Figs. 7 and 8. Although I have shown two tiers of horizontally extending rods 29, which serves to support the wet or moist articles which are to be dried, the spacing of said rods desirably is such as to provide adequate air space between articles suspended on adjacent rods of each tier to insure adequate contact with the air currents for promptly and effectively drying or dehydrating said articles.

To facilitate placing articles upon the rod or removing same therefrom, when the curtain 19 is drawn to one side, said rods may be swung laterally outward about their hinge connection to the support 25, as indicated in dotted outline in Fig. 9. To limit the amount of angular swing of the rods, and also to prevent accidental removal thereof from their pivoted ends from the members 25, I provide a pair of locking bars 38 for each support 25. Said bars of each pair extend in opposite lateral directions and are each rigidly secured at one end to the standard 10 by bolts 39. Said bars each extend over one half of the hinged or pivoted end portions of one set of rods as seen in Figs. 9, 10, 11, and have their outer ends downturned and rigidly secured to the ends of the 40 support 25 by the screws 40. Thus, if it is necessary at any time to remove the rods 29, the bars 38 may be quickly and easily detached by the removal of the bolts 39 and screws 40. As seen in the drawings, the dimensions of the bar 45

38 and the location of the rods 29 and the support 25 is such that the outermost rods 29 are capable of swinging about their pivoted connection to a maximum angle of approximately 30 degrees, and thus the other adjacent rods are limited in their outward swing by contacting the next outermost rod. As for example, the rod next to the outermost rod will be limited in its swing by contact with the outer rod at its maximum 10 position of movement, and the other rods will likewise be limited.

To counteract the strains set up in the frame structure tending to tip the same over when a large number of rods 29 are projecting freely in an angularly outward direction, I provide a pair of upwardly extending trusses or brace bars 42 at the end of the frame structure carrying the supports 25. Said bars 42 are each secured at their lower ends by means of bolts 43 to the outer portion of the respective members 12, constituting the foot at said end of the frame structure, as seen in Figs. 1, 3, and 16. The upper ends of said bars converge and are rigidly attached to the upper end of the standard 10 by means of 25 a bolt 44.

Referring now to the heating element which, as above mentioned, is a gas burner, it will be noted that the burner pipe 14 is provided intermediate its length, between the standards 10, 30 with a multiplicity of apertures 45 through which the gas is discharged under pressure and ignited. One end of the burner pipe protrudes beyond its corresponding fitting 11 and in which end is mounted a conventional form of orifice holder 35 48, having a restricted discharge aperture 49. The outer end of said orifice holder is threaded and connected to a conventional coupling 50 for attachment to a flexible conduit, not shown. It is to be understood, however, that if desired, permanent or rigid connections may be made between the threaded end of the holder 48 and the regular gas lines or pipes. The other end of said burner pipe, in the fitting 11, is sealed or closed in any desired manner, as by a plug (not shown). The end of the burner pipe 14, adjacent the discharge end of the holder 48, is provided with a 40 pair of diametrically opposite apertures 52, located in close proximity to and slightly forward of the gas supply orifice 49 for supplying air for admixture with the gas in proper proportions for insuring efficient combustion of the gas. These apertures 52 are controlled by a tubular sleeve 53 surrounding the outer end of the pipe 14, and having corresponding apertures 54 adapted to be aligned or registered with the apertures 55 52. Said sleeve 53 is connected to the pipe by a pair of screws 56 extending through slots 57 in said sleeve and anchored in the fitting 48. By virtue of this connection the sleeve 53 may be rotated around the pipe 14 for controlling the effective size orifices, determined by the relationship of the openings 54 in said sleeve, with respect to the openings 52 in the pipe 14.

Mounted above and in spaced relation to the burner pipe 14, in registration with the area in which the apertures 45 are located, is an elongated baffle plate 60 formed with a plurality of spaced-apart apertures 61 in registration with the pipe, as seen in Fig. 12. The function of this plate is to break up the heat currents, so as to diffuse or distribute them over a large area, and thus avoid confinement or concentration of the heat currents. Mounted below the burner pipe is a floor guard 62, of trough-like form of slightly greater length than the plate 60, and having its

marginal longitudinal edges inclined upwardly, as indicated at 63, and terminating approximately at the upper level of the pipe 14. The central bottom area of the guard member is provided with a plurality of longitudinally spaced apart apertures, 62^a through which a portion of the air draft is supplied to the burner. The purpose of the angularly disposed portions 63 is to prevent accidental extinguishment of the flame by sudden or severe drafts acting directly upon the 10 flame, and by virtue of the arrangement shown, the major portion of the air supply is compelled to travel through the restricted slots defined by the adjacent longitudinal edges of the plate 60 and the edges of the marginal portions 63 of the 15 member 62. This trough-like member 62 also serves to assist in directing the heat currents in an upward direction. If desired, the interior of said member 62 may be coated with any suitable heating reflective material. The plate 60 and 20 the member 62 are rigidly secured in place with respect to the burner pipe 14 by means of bolts 65 with spacer elements 66 interposed between the pipe 14 and the respective members 60 and 62, as seen in Fig. 16.

Mounted above the plates 60 is a baffle plate 68 of generally elongated rectangular form, supported in spaced-apart relation to the member 60 by means of two pair of brackets 69 connected to the outer marginal edges of the baffle plate, 30 adjacent the ends, by bolts 70, while the opposite ends of the brackets are rigidly connected to the pipe 14 by bolts 71. The baffle plate 68 has all of its marginal edges down-turned, as indicated at 68^a, which tend to preclude the rapid escape of the heat generated by the combustion of the gas. The heated air between baffle plates 60 and 68 thus is admixed with the continuous supply of fresh air entering below the lower edge of curtain 19, and such admixture is substantially uniformly distributed throughout the entire cross-sectional area of the drier, within the enclosure formed by the flexible curtain 19.

It will be apparent that due to the relatively large opening at the upper end of frame, as defined by the loop frame portion 15, and due to the termination of the lower edge of curtain 19 above the floor, a substantial draft is created when the burner is in operation. The natural convection currents produced by the burner thus cause a continuous influx of fresh air at the bottom, below the curtain 19, which air is admixed with the natural convection currents and circulated thereby substantially uniformly within the drier, around and over the articles to be dehydrated. This arrangement is such that the air, picking moisture from the wet or damp articles within the drier, is discharged through the large opening at the upper end of the frame, thus precluding recirculation of any appreciable amount of humid air.

To guard against any possibility of fire, due to contact with the baffle plate or the burner proper, by either the curtain or articles suspended from the rods, the entire burner and associated elements is enclosed by a reticulated panel or screen 73, which is disposed in spaced-apart relation to the burner assembly, as shown in Fig. 16. For convenience the screen is formed of a generally inverted cup-shaped cross-section with the marginal edges thereof terminating in close proximity to the floor. The opposite ends of the elongated screen are rigidly secured to flanges 74 of end panels 75, which preferably are formed of sheet metal and which form a complete closure 75

for the upper side of the burner structure. These end panels 15, as seen in Fig. 16, are provided centrally at the lower edge with an upwardly extending notch 16 for accommodating the burner pipe 14. Said panels are preferably located adjacent the respective standards or uprights 10, and are rigidly secured centrally thereof at their upper ends, to standards by bolts 18, while the lower outer ends are rigidly attached to the respective members 12 of the feet by bolts 43 and 43^a, the bolts 43 being of additional length for accommodating the truss members 42, as seen in Figs. 16 and 17. The end panels 15, by virtue of their connection to the foot members and the uprights 10, also serve as gusset plates for enforcing the frame structure. At the end adjacent the fuel inlet, the plate 15 is provided with an aperture 15^a, which is normally closed by a swingable plate 19, through which aperture access is afforded for igniting the burner.

By virtue of the drier construction above described it is possible to obtain a rapid drying of the moist or wet articles suspended on the rods 29, due to the fact that the natural convection currents cause an influx of a continuous and substantial supply of fresh air which becomes admixed with the convection currents and causes said admixture to intimately contact and dehydrate the articles suspended on the rods 29. The gas heater, as constructed, also insures a relatively uniform distribution of heat so as to insure substantially uniform drying of all the articles within the enclosure defined by the curtain 19. The construction of drier as herein disclosed may be easily moved around, assembled or disassembled in a compact form for convenience in storage or shipping.

Although I have herein shown and described a preferred embodiment of my invention, manifestly it is capable of modification and re-arrangement without departing from the spirit and scope thereof. As for example, relatively rigid sheet material may be employed in lieu of the flexible curtain 19, or electric or other heating means may be employed in lieu of the gas burner. I do not, therefore, wish to be understood as limiting this invention to the precise form herein disclosed, except as it may be so limited in the appended claims.

50 I claim:

1. In a clothes drier, in combination, an upright frame structure formed to provide a relatively large opening at its upper end, a heating element carried by the frame adjacent the floor, means carried on the frame above the heating element for supporting articles to be dehydrated, flexible sheet material supported at its upper edge on the upper portion of the frame and normally suspended in vertical direction forming a lateral wall for enclosing the article suspending means, the lower edge of said flexible sheet terminating above the floor to provide air-draft from all directions, and a reticulated body surrounding the heating element in spaced-apart relation and dimensioned to be engaged by the lower portion of said flexible sheet of material to support it out of contact with the heating element.

2. In a clothes drier, in combination, an upright frame structure including a pair of upright spaced-apart standards, and a closed loop connected to the upper ends of said standards; a heating element carried by the frame adjacent the floor, means disposed above the heating element for supporting articles to be dehydrated, including a support carried on one of said stand-

ards, and a plurality of transversely spaced-apart elements disposed in the same substantially horizontal planes, each of said last mentioned elements being pivotally connected at one end to said support, and adapted to be swung laterally about their pivot connections, and flexible sheet material extending around the frame to constitute a lateral wall for enclosing said article suspending means.

3. In a clothes drier, in combination, an upright frame structure including a pair of upright spaced-apart standards, and a closed loop connected to the upper ends of said standards; a heating element carried by the frame adjacent the floor, means disposed above the heating element for supporting articles to be dehydrated, including a support carried on one of said standards, and plurality of transversely spaced-apart elements disposed in the same substantially horizontal planes, each of said last mentioned elements being pivotally connected at one end to said support, and adapted to be swung laterally about their pivot connections, means on the other standard for supporting the free ends of said pivoted members, and flexible sheet material extending around the frame to constitute a lateral wall for enclosing said article suspending means.

4. In a clothes drier, in combination, an upright frame structure including a pair of upright spaced-apart standards, and a closed loop connected to the upper ends of said standards; a heating element carried by the frame adjacent the floor means disposed above the heating element for supporting articles to be dehydrated, including a support carried on one of said standards, and a plurality of transversely spaced-apart elements disposed in the same substantially horizontal planes, each of said last mentioned elements being pivotally connected at one end to said support, and adapted to be swung laterally about their pivot connections, means on the other standard for supporting the free ends of said pivoted members, and flexible sheet material extending around the frame to constitute a lateral wall for enclosing said article suspending means.

5. In a clothes drier, in combination, an upright frame structure formed to provide a relatively large opening at its upper end, a heating element carried by the frame adjacent the floor, means disposed above the heating element for supporting articles to be dehydrated, including a support carried on the frame and a plurality of transversely spaced-apart elements disposed in the same substantially horizontal planes, each of said last mentioned elements being pivotally connected at one end to said support, and adapted to be swung laterally about their pivot connections, means on the other standard for supporting the free ends of said pivoted members, said last mentioned support being formed with seats for receiving the free ends of the respective pivoted members for assisting in maintaining the latter in proper spaced-apart relation, and flexible sheet material extending around the frame to constitute a lateral wall for enclosing said article suspending means.

6. In a clothes drier, in combination, an upright frame structure including a pair of spaced-apart upright standards, a closed loop connected to the upper ends of said standards serving to define a substantial opening constituting a draft outlet, and a fluid fuel burner in the form of an elongated tube rigidly connected at its ends to the respective standards adjacent the floor and serving as a tie and brace for said standards;

means carried on one of the standards above the burner for supporting articles to be dehydrated, and flexible sheet material supported at its upper edge on said loop portion of the frame and normally suspended in vertical direction forming a lateral wall around the frame for enclosing the article suspending means.

7. In a clothes drier, in combination, an upright frame structure including a pair of spaced-apart upright standards, a closed loop connected to the upper ends of said standards serving to define a substantial opening constituting a draft outlet, and a fluid fuel burner in the form of an elongated tube detachably connected at its ends to the respective standards adjacent the floor, and serving as a tie and brace for said standards; said connections of the burner tube to the standards being such as to permit bodily reversal of the tube, end for end, means carried on one of the standards above the burner for supporting articles to be dehydrated, and flexible sheet material supported at its upper edge on said loop portion of the frame and normally suspended in vertical direction forming a lateral wall around the frame for enclosing the article suspending means.

8. In a clothes drier, in combination, an upright frame structure including a pair of spaced-apart upright standards, a closed loop connected to the upper ends of said standards serving to define a substantial opening constituting a draft outlet, and a fluid fuel burner in the form of an elongated tube rigidly connected at its ends to the respective standards adjacent the floor and serving as a tie and brace for said standards; an elongated guard plate disposed below the tube and having marginal up-turned edges terminating at a horizontal plane above the bottom of the tube, means carried on one of the standards above the burner for supporting articles to be dehydrated, and flexible sheet material supported at its upper edge on said loop portion of the frame and normally suspended in vertical direction forming a lateral wall around the frame for enclosing the article suspending means, said sheet material being formed so that at least a portion of its lower edge terminates a substantial distance above the floor to provide for influx of a continuous draft of air.

9. In a clothes drier, in combination, an upright frame structure including a pair of spaced-apart upright standards, a closed loop connected to the upper ends of said standards serving to define a substantial opening constituting a draft outlet, and a fluid fuel burner in the form of an elongated tube rigidly connected at its ends to the respective standards adjacent the floor and serving as a tie and brace for said standards; an elongated horizontally disposed plate mounted above and in spaced-apart relation to the elongated burner tube, an elongated guard plate disposed below the tube and having marginal up-turned edges terminating at a horizontal plane above the bottom of the tube, means carried on one of the standards above the burner for supporting articles to be dehydrated, and flexible sheet material supported at its upper edge on said loop portion of the frame and normally suspended in vertical direction forming a lateral wall around the frame for enclosing the article suspending means, said sheet material being formed so that at least a portion of its lower edge terminates a substantial distance above the floor to provide for influx of a continuous draft of air.

10. In a clothes drier, in combination, an up-

right frame structure including a pair of spaced-apart upright standards, a closed loop connected to the upper ends of said standards serving to define a substantial opening constituting a draft outlet, and a fluid fuel burner in the form of an elongated tube rigidly connected at its ends to the respective standards adjacent the floor and serving as a tie and brace for said standards; an elongated horizontally disposed plate mounted above and in spaced-apart relation to the elongated burner tube, a baffle plate mounted above and in spaced-apart relation to the first mentioned plate, and extending laterally therebeyond in a direction transversally of the burner tube, means carried on one of the standards above the burner for supporting articles to be dehydrated, and flexible sheet material supported at its upper edge on said loop portion of the frame and normally suspended in vertical direction forming a lateral wall around the frame for enclosing the article suspending means.

11. In a clothes drier, in combination, an upright frame structure comprising a pair of spaced-apart end standards each having a foot composed of two oppositely extending members adapted to engage the floor, a closed loop connected to the standards adjacent their upper end and dimensioned to define a relatively large opening for a draft outlet, and a fluid fuel burner including an elongated tube rigidly secured at opposite ends at the juncture of said standards and their respective feet and serving as a tie and brace for the lower ends of said standards; means carried on one of the standards above the burner for supporting articles to be dehydrated, and a flexible sheet of material supported at its upper marginal edge on the closed loop of the frame and suspended in a vertical direction, forming a lateral wall for enclosing the article suspending means.

12. In a clothes drier, in combination, an upright frame structure comprising a pair of spaced-apart end standards each having a foot composed of two oppositely extending members adapted to engage the floor, a closed loop connected to the standards adjacent their upper end and dimensioned to define a relatively large opening for a draft outlet, and a fluid fuel burner including an elongated tube rigidly secured at opposite ends at the juncture of said standards and their respective feet and serving as a tie and brace for the lower ends of said standards; a reticulated screen surrounding the burner in spaced-apart relation thereto and substantially coextensive therewith, end plates connecting the standards and the marginal end portions of the screen to support and reinforce the latter, means carried on one of the standards above the burner for supporting articles to be dehydrated, and a flexible sheet of material supported at its upper marginal edge on the closed loop of the frame and suspended in a vertical direction, forming a lateral wall for enclosing the article suspending means.

13. In a clothes drier, in combination, an upright frame structure comprising a pair of spaced-apart end standards each having a foot composed of two oppositely extending members adapted to engage the floor, a closed loop connected to the standards adjacent their upper end and dimensioned to define a relatively large opening for a draft outlet, and a fluid fuel burner including an elongated tube rigidly secured at opposite ends at the juncture of said standards and their respective feet and serving as a tie and brace

for said standards; a pair of upwardly extending brace members connected at their lower ends to the oppositely extending members of one of the feet, and their upper ends converging and rigidly connected to the standard adjacent its upper end, means carried on one of the standards above the burner for supporting articles to be de-hydrated,

and a flexible sheet of material supported at its upper marginal edge on the closed loop of the frame and suspended in a vertical direction, forming a lateral wall for enclosing the article suspending means.

JOSEPH W. JENSEN.
